UNITED STATES PATENT OFFICE.

GERTRUDE A. MACVEY, OF BROOKLYN, NEW YORK.

CIGARETTE BOX.

Application filed February 19, 1923. Serial No. 619,890.

To all whom it may concern:

Be it known that I, GERTRUDE A. MACVEY, a citizen of the United States, residing at Brooklyn, in the county of Kings and State 5 of New York, have invented certain new and useful Improvements in Cigarette Boxes, of which the following is a specification, reference being had to the accompanying drawings.

10 This invention relates to certain improvements in cigarette boxes and it is an object of the invention to provide a device of this general character with novel and improved means whereby a supply of matches may be 15 carried thereby.

Another object of the invention is to provide a novel and improved device of this general character wherein one end portion of a wall of the box proper is provided with 20 a return flap to receive a supply of matches together with means for maintaining the flap in applied position and the matches against displacement.

25 The invention consists in the details of construction and in the combination and arrangement of the several parts of my improved cigarette box whereby certain important advantages are attained and the device rendered simpler, less expensive and 30 otherwise more convenient and advantageous for use, as will be hereinafter more fully set forth.

The novel features of my invention will hereinafter be definitely claimed.

35 In order that my invention may be the better understood, I will now proceed to describe the same with reference to the accompanying drawings, wherein:

40 Figure 1 is a view in perspective of a box constructed in accordance with an embodiment of my invention;

45 Figure 2 is a vertical sectional view taken through the device as illustrated in Figure 1 with the large end flap of the tray in a position to conceal the matches;

Figure 3 is a view in plan of the blank from which the tray is formed;

Figure 4 is a view in plan of the blank from which the box is formed;

50 Figure 5 is a view in perspective illustrating a box constructed in accordance with a further embodiment of my invention;

55 Figure 6 is a longitudinal sectional view taken through a box constructed as in Figure 5 with the various parts in closed relation;

Figure 7 is a view of the blank from which the box proper is formed.

As disclosed in the accompanying drawings, 1 denotes a box constructed in a conventional manner from the blank B as illustrated in Figure 4 and with which is associated the sliding tray 2 in which the cigarettes are placed in the ordinary way. The tray 2 is preferably formed from a blank C 60 as illustrated in Figure 3.

A face wall 3 of the box 1 is provided at one end with a relatively short flap 4 which is returned to overlie the outer face of said wall 3, said flap being maintained in such 70 position by the wire staple 5 or the like.

Inserted between the flap 4 and the adjacent face wall 3 is a block or pack 6 of matches, the staple 5 or the like also serving to maintain said block or pack 6 in applied position. The outer face of the flap 4 is provided with an igniting surface 7 of suitable material. One end portion of the tray 2 is provided with a closing flap 8 of a conventional type while the opposite end portion of said tray 2 is provided with an elongated closing flap 9 which, when the tray 2 is housed within the box 1 is adapted to have its outer or free end portion inserted between the flap 4 and the block or pack 6 80 of matches, as particularly illustrated in Figure 2, whereby the matches under normal conditions are effectively protected.

In the form of invention illustrated in Figures 5, 6 and 7 the box 10 is constructed 90 in a conventional manner from the blank A illustrated in Figure 7. Associated with the box 10 is the tray 11 of the type now generally in use.

A face wall of the box 10 is provided at one end with a flap 12 which is returned to overlie the outer face of said wall and secured by a staple 14 or the like in the same manner as hereinbefore set forth with respect to the first embodiment of my invention. Associated with the flap 12 is a block or pack 15 of matches applied in the same manner as hereinbefore set forth with respect to the block or pack 6. The wall of the box 10 provided with the flap 12 is provided at the opposite end thereof with an elongated flap 16 which is adapted to have its outer or free end portion inserted between the flap 12 and the block or pack 15 whereby the matches 100 are effectively protected.

105 From the foregoing description it is thought to be obvious that a cigarette box 110

constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:-

15 As a new article of manufacture, a cigarette box having a face wall extended at one end to provide a relatively short integral flap, said flap being returned to overlie the

outer face of said wall, the outer face of the returned flap being provided with a striking 20 surface, a match pack inserted between the returned flap and the adjacent wall of the box, means disposed through the flap, the wall and the inserted portion of the match pack for holding the flap in overlying relation and the match pack against displacement, said face wall of the box at the end thereof opposite to the flap being provided with an integral elongated flap returned to overlie the outer face of said wall and of a 25 length to engage between the first named flap and the match pack to protect the pack.

In testimony whereof I hereunto affix my signature.

GERTRUDE A. MACVEY.
